UNITED STATES PATENT OFFICE.

FRITZ FÄRBER, OF DORTMUND, GERMANY.

ELECTRIC CONDUCTOR.

1,108,350.

Specification of Letters Patent. Patented Aug. 25, 1914.

Application filed December 2, 1913. Serial No. 804,275.

To all whom it may concern:

Be it known that I, FRITZ FÄRBER, a subject of the King of Prussia, German Emperor, and resident of Dortmund, in the 5 Kingdom of Prussia, German Empire, have invented an Improved and Novel Electric Conductor, of which the following is a specification.

The electric safety lamps hitherto employed in mines or other dangerous industrial works are generally constructed in such a way that the accumulator and the incandescence lamp are united in a solid casing. There is, however, a need in some industrial 10 works to have the lamp proper and the accumulator separated one from the other, both parts being then electrically connected by a flexible cord, but this arrangement has the drawback that in the case of an injury 15 to that cord short-circuiting may occur which then may give rise to an explosion if an explosive gas or gas mixture is present. Such a danger is obviated by my present invention, one form of execution of which is 20 illustrated as an example in the accompanying drawing, in which—

a is an electric accumulator, *c* the incandescence lamp proper, and *b* a flexible cord connecting the parts *a* and *c* with each other. 25 The gist of the invention now resides in using as conducting metal in the cord a metal the fusing point of which is very low, such, for instance, as lead or tin. If by any cause a short-circuit is produced in the cord, 30 for instance by one of the cord wires tearing or breaking, and piercing the insulating covering and coming in contact with the other wire so as to produce a short-circuit, then this latter will fuse the wire metal, but 35 no explosion will occur, because the fusing temperature amounts to about 400° C. only, whereas the ignition temperature of the explosive gas or gas mixture is considerably higher, *i. e.* about 700° C. In the case of 40 copper, however, an explosion would take place, as the fusing temperature of copper lies considerably above 700° C. and thus 45 white-heat already would ignite the explosive gas or gas mixture.

Electric circuits in which one of the conductors is made of an easily fusible metal have already become known, it is true, but they in general and the easily fusible conductor in particular formed a part of a fire alarm plant operated with constant current, 50 and the object was to interrupt this current and actuate thus the alarm mechanism if that conductor got fused in the case of a fire. Thus, although the means *per se* is already known, still, it is employed in the present 55 case in a novel combination and for a novel purpose, *viz.* in combination with safety lamps and for the purpose of interrupting the current in the case of a short-circuit by letting the conductor metal be fused at a 60 temperature which does not rise to the ignition temperature of the gas or gas mixture surrounding the lamp.

The sparks arising on opening a circuit operating with a current of from 2 to 4 65 volts, as generally used in connection with lamps of the kind in question, do not ignite a gas or gas mixture of the kind in question, and therefore if the connecting cord should 70 get torn this will not bring about an ignition of the explosive gases. Connecting 75 cords or conductors of this kind, as before described, may thus be regarded as explosion-proof.

Having now described my invention, what 70 I desire to secure by a Patent of the United States is:

The combination, with a battery and an electric safety lamp, of connecting conductors consisting of a metal the fusing 80 point of which lies below the ignition temperature of an explosive gas that may be 85 present in the space around said lamp, for the purpose as described.

In testimony whereof I affix my signature in presence of two witnesses. 90

FRITZ FÄRBER. [L.S.]
